TUBULAR GLASS SEALING APPARATUS
 John Lysak, Colonia, N.J., assignor to Radio Corporation
 of America, a corporation of Delaware
 Filed May 1, 1962, Ser. No. 191,586
 4 Claims. (Cl. 65—270)

This invention relates to apparatus for sealing tubular glass members, and more particularly to burner apparatus for sealing off an exhaust tubulation connected to evacuated envelopes, sometimes called a tipping torch.

In providing an envelope for an electron tube, a glass bulb having one end open is often used at the start. An electron tube mount is inserted into the bulb through the open end, the glass button or header of the mount being received within the bulb and partially closing the open end thereof. Flame is played on the bulb at the portion thereof adjacent the edge of the button, whereby the bulb and header are sealed together at the edge of the glass button to provide an envelope. In this process of producing an envelope, the leads extending through the button are usually received in holes in a supporting head and these leads are thereby protected from the sealing flames. The resultant tube enclosure or envelope is then evacuated and sealed off, or if desired, after evacuation and before sealing a preselected gas may be supplied within the envelope. In either case, a glass tubulation is provided for evacuating the envelope, and this tubulation may extend either from the end of the bulb opposite the header, or out of the header, in a known manner. This tubulation provides a path for the gases from within the envelope to the exhaust machine, and after the gases are exhausted through the tubulation (and if desired, the preselected gas is fed into the envelope through the tubulation), the envelope is sealed off by playing a flame on the exhaust tubulation, close to the envelope, and stretching the softened glass tubulation to close it off (tipping off) and to provide a vacuum-tight enclosure. The tip of the closed-off tubulation should be as short as possible to permit manufacture of a shorter tube and to avoid having a weak portion of the tube envelope that would result if the tubulation were long. If the tubulation extends out of the button and between the pins, the end of the tubulation or tip should be particularly short to permit inserting the pins of the finished tube into a socket.

To provide a short tip on a tubulation that extends out through the button or header and between the pins, the sealing flame is played on the tubulation as close to the button as possible. To prevent oxidation of the pins and to prevent cracking of the glass button by the heat of the sealing flame, the pins and the button should be protected from the sealing flame. Prior art tipping or sealing torches do not provide satisfactory protection for the pins and button from the sealing flame.

Furthermore, in known tipping torches, a plurality of flames are played on the tubulation, each flame requiring separate valving and control means, resulting in an expensive tipping torch assembly requiring skilled attention. Not only must the flames be separately controlled to provide properly burning gases, but also the several flames must be adjusted to center them on the tubulation. Furthermore, since the flames of the prior art tipping torches are long, because they extend from beyond the pins to the tubulation, prior art tipping torches are not economical in gas consumption.

It is an object of this invention to provide a burner apparatus particularly suitable for sealing off tubular glass members.

It is another object to provide a burner apparatus for tipping off an exhaust tubulation extending from the

2

glass button or header of an electron tube envelope and between the electrode leads or pins without greatly heating the leads, and without oxidizing the leads.

A further object of this invention is to provide a burner apparatus for tipping off an exhaust tubulation connected to an evacuated envelope.

It is a further object to provide a unitary burner or tipping torch structure that is easily adjustable, that shields the tube leads from direct flame, and that automatically centers the burner or tipping torch with respect to the tubulation that is to be tipped off.

It is a further object of this invention to provide apparatus which permits a short tip-off of the glass tubulation of a vacuum tube or the like.

It is another object of this invention to provide a torch that is economical of operation.

According to the invention, a tipping-off burner is provided which is annular in form and has a sector cut out of one side thereof, the flame produced thereby extending annularly inward of the annular burner. The tipping burner preferably is so mounted, adjacent an indexing exhaust turret that, in indexing the turret, the tubulation of an envelope to be sealed mounted in the turret exhaust head enters the annular tipping burner through the open side thereof, the pins sealed through and extending from the envelope header passing over the top of the burner. Means are provided for raising the burner until the pins contact a conical portion of the burner to center the header with respect to the burner. As the burner flame heats and softens the tubulation, the tubulation is stretched to close, and thereby to provide a seal. By suitable means, the tip-off burner is moved down far enough to clear the pins of the next envelope to be sealed which is mounted in the next exhaust head, and the next envelope is moved into sealing position, and the sealing process repeated.

This invention is described in detail in connection with the accompanying drawing in which:

FIG. 1 is a partial plan view of an exhaust and tipping apparatus embodying the tipping burner and the means for mounting it;

FIG. 2 is a front elevation of the apparatus of FIG. 1;

FIG. 3 is a sectional view on the line 3—3 of FIG. 1;

FIG. 4 is a plan view of the tip-off burner of this invention;

FIG. 5 shows a section of the burner of FIG. 4 on line 5—5 thereof and also shows a partial section of a vacuum tube mounted thereon;

FIG. 6 is a plan view of a modified tip-off burner; and,

FIG. 7 shows a section of the burner of FIG. 6 and also shows a partial section of a vacuum tube mounted therein.

The general layout of the apparatus embodying this invention is shown in FIGS. 1, 2 and 3. The apparatus includes an indexable turret 10 (partially shown) which comprises a complete annulus which rotates in an indexed manner about its center. A plurality of exhaust heads 12 are provided on the turret 10, these heads 12 each comprising an annulus 13 of resilient material with the hole in the top thereof for receiving a tubulation 14. Exhaust pipes 16 connect the exhaust head 12 to an exhaust machine, not shown. The apparatus further comprises a stationary support 18 adjacent and below the turret 10. The support 18 supports a plurality, here two are shown, of preheat burners 20, a basket 24 and a tip-off burner 22. The preheat burners 20 may take any known form and are mounted on support 18 to direct their flames on the tubulation 14 below the pins 26 of the tube 28, to gradually heat the tubulation in

preparation for the tip off thereof and without greatly heating the pins.

The tip-off torch or burner 22 is also mounted on table 18 by means of shaft 30 and in registry with an exhaust head 12. The shaft 30 is slidably mounted for axial motion on support 18 by means of bearing 32. An offset portion 34 of shaft 30 is fixed to and supports burner 22 in a manner such that the axis of the burner is vertical. The lower end of shaft 30 holds a roller or cam follower 36. The roller 36 rides on the top of cam 38. The cam 38 is fixed to shaft 40, to rotate therewith, whereby as the shaft is rotated in proper synchronism with the indexing of turret 10, the burner 22 is moved from the solid line position thereof shown in FIG. 3 to the dotted line position thereof in FIG. 3. The dotted line position of burner 22 in FIG. 3 corresponds to the position of the burner shown in FIG. 2.

The basket 24 is tiltably mounted on support or table 18 by means of standard 42 and bent lever 44. One portion 46 of lever 44 is fixed to and supports basket 24. A portion 48, integral with portion 46, extends radially out from turret 10. A portion 50 of lever 44 integral with and at right angles to portion 48, extends through and is pivotally mounted on standard 42. The outer end of lever 44 is linked to the top of rod 52. The lower end of rod 52 is pivotally connected to one end of lever 54. The other end of lever 54 is pivoted in bracket 56. A roller or cam follower 58 is rotatably mounted on lever 54 and contacts cam 60 which is fixed to shaft 40 on one end of shaft 40 remote from cam follower 36. As shaft 40 rotates, the cam causes basket 24 to move from the position shown in solid lines in FIGS. 1, 2 and 3 to the position thereof shown in phantom in FIG. 3. At its top position, the tube falls out of the basket into a chute, not shown. A spring (not shown) keeps roller 58 in contact with cam 60.

The preferred form of a tip-off burner 22 is shown in FIGS. 4 and 5. This burner includes an upper plate 50 and a lower member 52. The upper plate 50 comprises two spaced parallel annular portions, an upper portion 56 and a lower smaller portion 59 being integrally connected by a funnel or frustro-conical portion 60. The portion 60, which comprises a radially inward surface of the annular burner, slants outwardly in an upward direction, so that the upper portion 60 is radially outward of the lower portion 59. A plurality of gas jet tubes 62, four being shown in FIG. 4, extend radially inwardly from the funnel shaped portions 60 of the upper plate 50 for a purpose to be disclosed. The inner ends of the gas tubes 62 end above the inner edge of disk 59. The tubes 62 are directed radially inward and may be tilted slightly upwardly with respect to a plane through the disk 59. The lower cup-shaped member 52 is annular and comprises an outer cylindrical portion 64 and a short inner cylindrical portion 66, the cylindrical portion 64 and 66 being integrally joined by an annular base portion 68. Threaded holes are provided in the outer cylindrical portion 64 to receive screws 67 which extend through corresponding holes in disk 56 for holding the plate 50 and member 52 in assembled position. A sector is cut out of both the upper plate 50 and the lower member 52 as shown at 70 in FIG. 4 to permit the tubulation 14 to enter into the middle of burner 22 from the side thereof. The lower member 52 has end walls 72 adjacent the cut-out portion to provide a hollow interior comprising a gas chamber 73 between members 50 and 52 in the burner assembly. A gas connector 74, fixed to the lower portion 52, communicates with the gas chamber 73. The plate 50 and the member 52 are so proportioned that when fixed together by screws 67 an inwardly directed slot 75 is provided between the member 52 and plate 50. When gas is fed to burner 22 through connector 74, gas enters chamber 73 and gas jets are formed at the ends of gas tubes 62. Also, gas is fed annularly inwardly in a sheet-

like manner through slot 75. The slot is closed off at the cut-out sector 70 by the end walls 72.

As best shown in FIG. 5, when an electron tube 28 is received in burner 22, the pins 26 of the tube are centered with respect to the burner 22 by contact of the pins or leads 26 with the funnel or frustro-conical portion 60, and the gas tubes 62 extend between the pins 26, the ends of these tubes 62 being within the circle of pins 26. Thereby, flame jets from tubes 62 play on the tubulation 14 up near the glass button 29 to heat the tubulation 14 to sealing temperature. It has been found that the gas jets produced by gas tubes 62 which are small enough to extend between the pins 26, will not stay lit by themselves alone. The partially annular flame produced by slot 75 serves to keep these jets lit and does not cause appreciable softening of the tubulation 14. Since the flames from jet 62 and slot 75 are quite small, this tipping burner is economical in the use of gas.

A modified tipping burner is shown in FIGS. 6 and 7. This burner 80 also comprises two parts 82 and 84 fixed together by screws 86. The upper part 82 comprises an upper smaller annular element or portion 88 and a lower larger element or portion 90 connected by a frustro-conical portion 92. The surface of radially outward portion 92 slants outwardly in a downward direction. If desired, a lip 94 may be formed on the lower or inner surface of upper annular portion 88. The lower part 84 comprises two concentric cylindrical portions 96 and 98. The outer cylindrical portion 96 has a thick wall for receiving the screws 86. The two cylindrical portions 96 and 98 are integrally connected by an annular portion 100. The inner cylindrical portion 98 extends upwardly from portion 100 in registry with the lip 94. Cylindrical portion 98 terminates short of lip 94 to provide a slot 102 between the end of cylinder 98 and lip portion 94. As shown in FIG. 6, a sector of the burner is cut away at 104 to permit the tubulation to enter the center of the burner from the side thereof. The burner is provided with the end walls 106 to prevent gas from escaping from the burner except at the slot 102. The two portions 82 and 84 together with the wall ends 106 provide a hollow burner, the interior of which provides a gas chamber 107 to which gas is fed by gas fitting 103. Upon lighting the gas escaping from inwardly directed slot 102, a partially annular sheet of inwardly directed flame is produced by the burner 80.

FIG. 7 also shows the relationship of the pins 26 of the electron tube 28 and the burner 80 whereby the tubulation 14 is centrally positioned of the burner 80. As shown, the pins 26 by contact with the conical portion 92 are centered with respect to the burner and when so centered are positioned outside of the flame in a radial direction. Since the flame is directed inwardly from slot 102, flame does not play on the pins 26. The tubulation is centered with respect to the flame by the cooperation of the pins with the conical portion 92, and the flame produced by the burner 80 plays directly on the tubulation 14. The slot 102 may be formed to direct the sheet of flame produced thereby either up or down, as desired to provide a seal at the desired part of the tubulation 14. Since the slot is very close to the tubulation, the flame is quite small resulting in a gas saving over the prior art tipping burners discussed above.

The operation of this sealing apparatus is as follows: the operator puts the tubulation 14 of an electron tube into the resilient annulus 13 of a vacant exhaust head 12, for example, the right-hand one, as viewed in FIG. 1. The electron tube 28 is supported by its tubulation 14 on the chuck 12. The turret is indexed counter-clockwise, as viewed in FIG. 1. The tube 28 may be exhausted in a known manner.

When the exhaust head arrives near the tip-off position, for example, at the left-hand position, as viewed in FIG. 1, after having gone nearly around once, warm up flames are played on the tubulation 14 by burners 20 to gradually

warm the tubulation 14 so that application of the tipping torch head, at a later step in the operation will not cause cracking of the tube enclosure. The warm-up flames are applied below the pins 26 to avoid oxidizing them.

As the tube is brought to a tipping off position, the basket 24 and the tipping torch 22 at the tipping position of the turret 10 are in the position shown in solid lines in FIG. 3, that is, the torch is in its low position so that the pins 26 of the tube 28 will clear the torch 22 and so that the tubulation 14 may enter the center of torch 22 through the slot 70. The basket 24 is also in its lowest position so that the basket 24 will receive the glass envelope of the tube 28 through the open side of the basket 24 with pins 26 and tubulation 14 extending downwardly through the open bottom portion of the basket 24. Cam 38 then raises torch 22 to its upper position and the funnel portion 60 (see FIG. 5) centers the pins 26 and therefore also centers the tubulation 14 with respect to the torch 22. Since the tubulation is relatively long and since the chuck 12 comprises rubber parts, the slight adjustment of the positions of the tubulation 14 that may be necessary places little or no strain on the electron tube 28. The flame from jet tubes 62 play on the tubulation 14 up near the button 29 to soften the tubulation. When the tubulation is softened to the proper extent, the burner 22 and the basket 24 are both raised by cams 38 and 60 respectively to stretch the tubulations at its softened part. Then the basket 24 is moved to the position shown in phantom in FIG. 3, whereby the tube 28 is thrown into a chute, not shown. The turret is then indexed to move the sealed off tubulation remaining in the chuck to its next indexed position, and immediately after the sealed tubulation passes the basket 26 and the torch 22, rotation of cams 60 and 38 cause the torch and the basket to take the portions shown in solid lines in FIG. 3 ready to receive the next electron tube 28. The operator removes the tubulation 14 from the chuck 12 and the cycle is completed.

Obviously, tubes having the tubulation extending from other parts of the envelope may be tipped off with the burner of this invention. In such cases, the burner 22 will function to seal the tubulation 14 even though no pins 26 come into contact with any part of the burner 22.

If the burner 80 of FIGS. 6 and 7 is used instead of the burner 22 of FIGS. 4 and 5, the centering of the pins 26 with respect to the burner 80 is performed by contact with the pins 26 with conical portion 92. The operation is otherwise the same, the tubulation 14 entering the center of burner 80 from the side and through the slot 104.

What is claimed is:

1. A tipping torch for use with an electron tube having a header wafer and a plurality of leads extending from said wafer, said leads being arranged in a circle, said torch comprising:

a hollow annular member of sectoral shape,
a first inner surface portion of said torch being frusto-conical in shape,

the large diameter end of said frusto-conical surface portion having a diameter larger than said lead circle, and another region of said frusto-conical surface portion having a diameter substantially the same as said lead circle for centering said leads with respect to said torch,

at least one gas tube communicating with the interior of said hollow member, said tube extending radially inwardly from said frusto-conical surface portion and terminating within said lead circle when said leads are engaged with and centered by said frusto-conical surface portion,

a second inner surface portion connected with said frusto-conical surface portion and lying within a projection of said lead circle when said leads are engaged with and centered by said frusto-conical surface portion, said second surface portion having a slot extending outwardly therefrom and communicating with the interior of said hollow member, and

means to supply gas to the interior of said hollow member.

2. A tipping torch for use with an electron tube having a header wafer and a plurality of leads extending from said wafer, said leads being arranged in a circle, said torch comprising:

a hollow annular member of sectoral shape,
a first inner surface portion of said torch being frusto-conical in shape,

the large diameter end of said frusto-conical surface portion having a diameter larger than said lead circle, and another region of said frusto-conical surface portion having a diameter substantially the same as said lead circle for centering said leads with respect to said torch,

at least one gas tube communicating with the interior of said hollow member, said tube extending radially inwardly from a position on said frusto-conical surface portion between the large diameter end of said frusto-conical surface portion and said another region of said frusto-conical surface portion, said tube terminating within said lead circle when said leads are engaged with and centered by said frusto-conical surface portion,

a second inner surface portion connected with said frusto-conical surface portion and lying within a projection of said lead circle when said leads are engaged with and centered by said frusto-conical surface portion, said second surface portion having a slot extending outwardly therefrom and communicating with the interior of said hollow member, and means to supply gas to the interior of said hollow member.

3. A tipping torch for use with an electron tube having a header wafer and a plurality of leads extending from said wafer, said leads being arranged in a circle, said torch comprising:

a hollow annular member of sectoral shape,
a first inner surface portion of said torch being frusto-conical in shape,

the large diameter end of said frusto-conical surface portion having a diameter larger than said lead circle, and the small diameter end of said frusto-conical surface portion having a diameter substantially the same as said lead circle,

at least one gas tube communicating with the interior of said hollow member, said tube extending radially inwardly from said frusto-conical surface portion and terminating within said lead circle when said leads are engaged with and centered by said frusto-conical surface portion,

a second inner surface portion of said torch lying within a projection of said lead circle when said leads are received within said frusto-conical surface portion,

the small diameter end of said frusto-conical surface portion and said second surface portion being joined by a third surface portion, said third surface portion and said frusto-conical surface portion coacting to position said leads with respect to said torch, said second surface portion having a slot extending outwardly therefrom and communicating with the interior of said hollow member, and means to supply gas to the interior of said hollow member.

4. A tipping torch for use with an electron tube having a header wafer and a plurality of leads extending from said wafer, said leads being arranged in a circle, said torch comprising:

a hollow annular member of sectoral shape,
a first inner surface portion of said torch being frusto-conical in shape,

the large diameter end of said frusto-conical surface portion having a diameter larger than said lead circle, and the small diameter end of said frusto-conical

cal surface portion having a diameter substantially the same as said lead circle,
 a second inner surface portion of said torch being cylindrical, said cylindrical portion being coaxial with said frustro-conical portion and having a diameter 5 smaller than the diameter of the small diameter end of said frustro-conical portion,
 a disk-like portion connecting said cylindrical portion and the small diameter end of said frustro-conical portion, said disk-like portion and said frustro-conical portion coacting to position said leads with respect to said torch,
 at least one gas tube communicating with the interior 10 of said hollow member, said tube extending radially inwardly from said frustro-conical surface portion between the large and small diameter ends thereof and terminating within said lead circle when said leads are engaged with and centered by said frustro-conical surface portion,
 15

said cylindrical portion having a slot extending outwardly therefrom and communicating with the interior of said hollow member, and means to supply gas to the interior of said hollow member.
